CLAIM

The ornamental design for a Y-type fitting for two showerheads, as shown and described.

DESCRIPTION

FIG. 1 is a perspective view of a Y-type fitting for two showerheads showing my new design;

FIG. 2 is a front elevational view thereof, the rear being the same as the front shown;

FIG. 3 is a side elevational view from one side thereof, the opposite side being the same as the side shown;

FIG. 4 is a bottom plan view thereof.
